COMBINED PRINTING MACHINE AND METER FOR TICKET VALIDATION

Robert C. Ringholz, 436 Court St.,
San Bernardino, Calif. 95023

Filed Feb. 10, 1966, Ser. No. 1,003

Term of patent 14 years

(Cl. D64—11)

FIGURE 1 is a perspective view showing two adjacent sides and the top of a combined printing machine and meter for ticket validation embodying my new design;

FIGURE 2 is a perspective view on smaller scale of the side and adjacent side opposite to that shown in FIGURE 1; and

FIGURE 3 is an end elevational view thereof as seen from the right of FIGURE 2.

I claim:

The ornamental design for a combined printing machine and meter for ticket validation, as shown.
